US00D808713S

(12) **United States Design Patent** (10) **Patent No.:** **US D808,713 S**
(45) **Date of Patent:** **** Jan. 30, 2018**

(54) **LID**

(71) Applicant: **YETI Coolers, LLC**, Austin, TX (US)

(72) Inventors: **Mark Rane**, Austin, TX (US); **Dustin Bullock**, Austin, TX (US); **Ian Cunningham**, Austin, TX (US)

(73) Assignee: **YETI Coolers, LLC**, Austin, TX (US)

(**) Term: **15 Years**

(21) Appl. No.: **29/587,376**

(22) Filed: **Dec. 13, 2016**

(51) LOC (11) Cl. **07-01**

(52) U.S. Cl.

USPC **D7/396.2**; D9/443

(58) **Field of Classification Search**

USPC D7/316, 392, 392.1, 396.2, 397, 510,
D7/533; D9/434–436, 438, 439, 440,
D9/443, 444, 447–450, 452–454, 499,
D9/549, 715, 717–719; D23/260, 269,
D23/390

CPC B65D 25/42

See application file for complete search history.

Oct. 11, 2016 [earliest online date], [site visited Jul. 31, 2017]. Available from Internet, <URL:https://www.amazon.com/Glink-Standard-Plastic-Multi-Compatible-Stainless/dp/B01MREDI8K>.*

Primary Examiner — Robert M Spear

Assistant Examiner — Darcey E Heflin

(74) Attorney, Agent, or Firm — Banner & Witcoff, Ltd.

(57) **CLAIM**

The ornamental design for a lid, as shown and described.

DESCRIPTION

FIG. 1 is a top, front, left perspective view of a lid showing our new design in an open position;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top, front, left perspective view of a lid showing our new design in a closed position;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

In the drawings, the claim is limited to the shaded surfaces. The broken lines showing portions of a lid depict environment and form no part of the claim.

1 Claim, 13 Drawing Sheets
